NOVEL SHOE CONSTRUCTION

Meyer Margolin, Elgin, Ill.

Application November 11, 1944, Serial No. 562,996

1 Claim. (Cl. 36—30)

1

My invention relates to a novel type of play shoe or platform shoe and more particularly my invention relates to a novel comfortable play shoe or platform shoe such as for example the California type shoe.

Play shoes and platform shoes are common in the art but they have certain undesirable characteristics, among which are lack of a desirable flexibility, rigidity both longitudinally and transversely and unyielding hardness of sole and foot support.

Accordingly, although the style and appearance of this type of shoe is attractive and creates a demand, the sale of this type of shoe has been retarded by its lack of comfort.

It is the object of the present invention to provide a novel type of play shoe having a soft and resilient sole or foot support.

It is a further object of the present invention to provide a novel type of shoe of the so-called California type characterized by novelty and style and have comfort and flexibility in wear.

It is a further object of my invention to provide a novel insole and middle sole structure for imparting to a shoe of the type described increased comfort and flexibility.

It is a further object of the present invention to provide a shoe of novel appearance but with feature of comfort hitherto unobtainable in the art.

The objects of the present invention are accomplished by providing a relatively thick insert so disposed in the center of the forepart of the foot so that a resilient and comfortable support is afforded to the foot. The insert is disposed substantially centrally with respect to both the insole and the middle sole and is held in place by a so-called sole cover and outsole.

I may also employ a sole or middle sole of resilient material such as cork or rubber, provided with a central resilient insert, the insole of resilient material being bound firmly by a material to enable it to be properly secured with respect to the shoe upper.

The specific structures by means of which the objects of my invention are obtained are specifically set forth hereinafter. In this connection reference is made to the drawing in which

Figure 1 is a side view in partial section of the novel shoe of my invention.

Figure 2 is a cross section of the forepart of a modified form of the shoe of my invention.

Figure 3 is a detailed view of that side portion of the shoe where the upper is joined to the insole

2

showing the manner of securing the upper on to the shoe bottom.

Figure 4 is a side view in partial section of a modified form of the shoe of my invention.

5 Figure 5 is a front cross sectional view of a still further modified form of my invention in which the insert has grooves and perforations.

Figure 6 is a detailed showing of a side portion of the shoe of my invention illustrating the binding on the middle layer and the manner in which the upper is secured.

Referring now more specifically to the drawing, in Figure 1 I show a shoe comprising an upper 10, a heel portion 11 and an outsole 12.

15 The feature of this construction lies in the fact that disposed in a common opening in the insole 13 and the relatively thick middle sole 14 is disposed a resilient insert 15.

The resilient insert 15 may be formed of rubber, sponge rubber, soft cork or any other suitably resilient and soft material. A sock lining 16 is disposed over the insole 13 and the insert 15. The exposed peripheral portions of the insole 13 and the middle sole 14 are protected by 20 bindings 18 and 19.

25 In the resilient insert 15 are disposed perforations 20 which extend therethrough to provide increased resilience and ventilation. By providing the single resilient insert 15 in the common 30 opening provided in the forepart of the insole 13 and the middle sole 14, I provide both for increased softness and resilience in the support for the forepart of the foot and I also firmly fix or position the insole 13 and the middle sole 14 with 35 respect to one another to prevent their shifting in the course of wear or flexing.

It will be noted that the middle sole and the insole lie in a novel position with respect to the general shoe assembly.

40 In Figure 2 I show a cross section of the forepart of a shoe as described in connection with Figure 1, the modified form of Figure 2 distinguishing in that the insert 22 is provided with 45 grooves 23 as well as perforations 24. The upper 30 is lasted to the insole 31 and the middle sole 32 is bound with a binding 33. The outsole 34 is secured to the middle sole. It will be noted that the resilient insert 22 occupies a common cavity of the insole 31 and the middle sole 32.

45 In Figure 3 I show a modified form of my invention in which the middle sole 40 may comprise a resilient material such as rubber or cork. The insole 41 may also be formed of a resilient material such as rubber or cork. I have found that 50 by providing a binder such as 42 on the middle

55 by providing a binder such as 42 on the middle

sole 40 and a binder 43 on the insole 41 about the peripheral exposed edges of such middle sole and insole, that I can while providing a desirable decorative effect also permanently restrain the resilient insole or middle sole from spreading or squeezing out under pressure of the foot in the shoe.

In Figure 4 I show a platform type of shoe in which the upper 50 is secured as shown specifically in Figure 6 to the binding 51 and the sock lining 52. The platform is provided by a relatively thick middle sole 53 in the center of the forepart of which is disposed a resilient insert 54 of rubber or the like. In the resilient insert 54 are grooves 55 and perforations 56 to provide for increased comfort, flexibility and air transmission.

The edges of the middle sole 53 are firmly bound with a binder 51 which as pointed out above is secured to the upper 50. The sock lining 52 together with the outsole 57 maintain the resilient insert 54 in its proper position in the opening in the forepart of the middle sole 53.

The resilient insole and middle sole can extend either from the toe to the ball portion of the shoe or it can extend entirely from toe to heel. The insert 54 may be provided with a peripheral extending lap 59 which extends over the adjacent portion of the middle sole 53 and is secured thereto by stitching not shown. Similarly the various resilient inserts described in the various modified forms of my invention herein may be provided either with a single lap or both an upper and lower lap which extend over in the form of a graduated feather edge over the adjacent portion of the middle sole or insole.

By the structures herein described, I provide a play shoe or platform type of shoe having both transverse and longitudinal flexibility with greatly increased foot comfort by reason of the soft and resilient supporting portion in the forepart of the shoe and by the provision of the binding and lasting of upper as described I secure at the same time a permanently firm shoe structure. Thus, I obtain the desirable thick platform effect without sacrificing the comfort of the shoe to the wearer.

I may also employ this platform type construction that I have described, particularly the thick middle sole, in making ordinary shoes for men and women that will apparently add to the wearer's height. That is, by means of the thick middle sole or by means of a thicker insole that is concealed, increased height is given to the wearer

without the cause thereof being revealed. For the insole or middle sole of increased thickness, I may either employ the insert construction I have shown, or I may use various types of insoles and middle soles that are rendered flexible by slashes extending transversely across the bottom of the middle sole or insole, such as straight line transverse slashes or zig-zag generally transverse slashes.

I may also employ a multiplicity of punches or perforations in the insole or middle sole, which punches or perforations will both increase the flexibility of that element as well as lighten its weight. Light weight is important because of the increased thickness of the middle sole or insole.

My construction in which I use a resilient insert in the forepart as shown in the drawing and described herein is particularly desirable because I may then employ a very thick middle sole without sacrificing flexibility and comfort of the shoe. In fact the very thick insert such as 15 shown in Figure 1 is extremely comfortable since a considerable resiliency is afforded to the ball of the foot.

Generally speaking a shoe having a very thick middle sole would be uncomfortable because of its stiffness and hardness and these disadvantages are overcome by my present invention.

The extremely thick resilient insert 22 such as 15 in Figure 1 and 22 in Figure 2 or 54 in Figure 5, enables me by reason of the openings therein such as the perforations and the grooves to obtain a considerable forced breathing or pumping action of air as the insert is flexed and pressed in the act of walking.

Various modifications of my invention will suggest themselves to those skilled in the art. I accordingly desire that in construing the breadth of the appended claim, they shall not be limited to the specific details shown and described in connection with the above explanation.

I claim:

In a shoe of the class described, an upper, an insole having a centrally disposed opening in its forepart, a middle sole having a similar opening registering with said opening in said insole, said insole comprising a resilient material and having a binding about the peripheral edges thereof, said middle sole having a binding about the peripheral edges, a rubber-like insert disposed in said common opening in the forepart of said insole and middle sole, and a sock lining overlying said insole and covering said filler.

MEYER MARGOLIN.
